SEWING MACHINE

Otto R. Haas, Beverly, Mass., assignor to United
Shoe Machinery Corporation, Flemington, N. J.,
a corporation of New Jersey

Application January 29, 1944, Serial No. 520,259

10 Claims. (Cl. 112—62)

The present invention relates to improvements in machines for sewing the corner seams of leather bags or like articles, the parts of which are secured together by stitches passing through their abutting edges at an inclination to both the adjoining faces of the completed bag or article, and is hereinafter illustrated as embodied in a bag sewing machine of the type disclosed in United States Letters Patent No. 1,614,444, granted January 11, 1927, upon an application 10 filed in the name of Robert G. Reid et al.

The object of the invention is to provide in a bag corner sewing machine, a novel and improved construction and arrangement for supporting the work with the parts in correct sewing relationship, without the necessity of making complicated or extensive adjustments in the machine requiring the services of an experienced and skillful operator. Other objects are to provide a bag corner sewing machine with a work support of generally more simple and effective construction than heretofore and to avoid difficulties ordinarily encountered in the use of prior machines for sewing corners of bags or similar articles.

In the operation of bag corner type sewing machines, particularly those intended for operation upon thick, heavy materials requiring the use of a curved hook needle and an awl to penetrate the required thicknesses of adjacent bag parts, it is desirable to present the unsewed corner of a bag to the stitch forming devices in such a way that the stitches will be inserted as deeply as possible within the material operated upon without breaking through into the inner corner of the completed bag to expose the threads of the stitches. Where light-weight materials are utilized in order to prevent deflection of the parts and improper insertion of the stitches during sewing, it is necessary to support the bag parts as closely as possible about the point of operation of the needle and awl. It is the usual practice, therefore, to provide a work support having angularly disposed surfaces and close-fitting needle and awl receiving openings. To render the machine effective for different thicknesses of work, the work support is mounted for adjustment toward and from the needle and awl paths and, in order to obtain the best results, the work support must be carefully adjusted with respect to the needle and awl paths for each change in work thickness, it being necessary, in actual practice, to sew several sample corners after an adjustment has been made for the purpose of ascertaining the best possible location of the work

support surfaces. Frequently, the adjustments are of a complicated nature requiring many slight changes in position of the support before a bag may be sewed successfully. A substantial amount of time and the exercise of unusual skill on the part of the operator may be required for these adjustments, particularly where the bag being sewed is composed of two parts having different thicknesses.

To avoid these difficulties and in the attainment of the several objects of the present invention, the illustrated embodiment thereof resides in a work support for a bag corner sewing machine in which the edge and side surface abutting bag parts are held in place by relatively adjustable members, the movement of one of which is so guided that, regardless of adjustments, the exposed threads in the stitches will be inserted at the desired location on the side of the bag part which engages it without changing the location of the exposed threads in the stitches on the other part of the bag for any adjustment of the work support. The adjustable members of the work support are so arranged that oversize needle and awl receiving openings in the members are not required. Thus, simple and effective adjustments may be made in the work support for sewing bags of different shapes and sizes or having parts of varying thicknesses with an assurance that workmanlike results may be obtained immediately following adjustments without resorting to a time and material consuming process of trial and error.

These and other objects and features of the invention will become apparent from the following description taken in connection with the accompanying drawings, in which:

Fig. 1 is a view in side elevation and partly in section of those parts of a lockstitch hook needle sewing machine embodying the work supporting means and features of adjustment of the present invention, the corner of a bag being illustrated in section at a sewing position on the supporting means;

Fig. 2 is a view similar to Fig. 1, with additional parts broken away and shown in section, illustrating adjustments of the work supporting means different from those of Fig. 1, the material of one of the illustrated bag parts being thicker than that shown in Fig. 1;

Fig. 3 is a view of the work supporting means illustrated in Fig. 1, looking in the direction of the arrow III of that figure;

Fig. 4 is another view of the same parts, look-

ing in a direction at right angles to the arrow in Fig. 1;

Fig. 5 is a perspective view of the abutment members of the work supporting means, showing a portion of a bag in sewing position thereon;

Fig. 6 is a detail perspective view of one of the abutment members for the work supporting means;

Fig. 7 is a detail perspective view of the other abutment member for the work supporting means;

Fig. 8 is a similar view of a work engaging plate of the first-mentioned abutment member; and

Fig. 9 is a perspective view of a portion of the bag, looking from the outside.

The illustrated sewing machine is a lockstitch curved needle machine for uniting the edges of a heavy leather or other tough material to form a bag corner, illustrated in Fig. 9. The machine has a construction and mode of operation substantially the same as that disclosed in United States Letters Patent No. 1,169,909, granted February 1, 1916, upon an application filed in the name of Fred Ashworth, and in the Reid et al. patent above referred to. As in the Reid et al. patented machine, the work support of the illustrated machine has work engaging abutments formed with adjacent external faces disposed at an angle of 90° to each other. To clamp the bag parts in position on the work support, the machine is equipped with a work supporting horn, not shown, similar to that disclosed in United States Letters Patent No. 1,695,718, granted December 18, 1928, upon an application filed in the names of Fred Ricks and Robert G. Reid. In some instances, the bag being operated upon is presented to the work support with its parts mounted upon a form or frame similar to that disclosed in the Reid et al. patent above referred to. The machine is also provided with a curved hook needle 2, a work penetrating and feeding awl 4, and other stitch forming devices similar to those in the patents.

The machine of the Reid et al. patent is entirely satisfactory in its operation while sewing together bag parts having uniform thickness in which the end surface of one part abuts the side marginal surface of another part with stitches disposed at an angle to the abutting surfaces. When the parts operated upon have a thickness greater than usual, unless adjustments are made to prevent it, the thickness of the side abutting part will hold the abutting surface of the end abutting part entirely out of the paths of the needle and awl, or at least will cause the stitches to be inserted at an insecure depth in the end of the end abutting part. To overcome this difficulty, the Reid et al. machine is provided with means for changing the position of the work support bodily to bring the apex of the angle formed by the work supporting surfaces of the work support farther away from the needle path, and for changing the angle of the work support with respect to the needle path where necessary. Adjustments for making these changes must be made carefully and require the expenditure of valuable time and effort for satisfactory results. Furthermore, bag parts or test pieces of material operated upon may be wasted during a necessary process of trial and error required in determining the adjustments best suited for the thicknesses operated upon. Also, in the patented machine, the apex of the angle between the work supporting surfaces of the work support is movable with relation to the needle path. Suitable enlarged openings, there-

fore, must be formed in these surfaces to clear the needle path and, as a result, their size may be such that insufficient support is provided when relatively thin work is operated upon.

To enable corners of bags, the parts of which are composed of different thicknesses of material, to be sewn satisfactorily without the exercise of special skill or ability by the operator or loss of time and expenditure of effort in adjusting the work support of the machine, while at the same time providing adequate support for the bag parts adjacent to the needle path, the machine embodying the present invention is provided with a two-part work support having relatively movable abutments with work supporting surfaces disposed at right angles and formed with needle and awl receiving slots 6 and 8 fitting closely with the sizes of the needle and awl 2 and 4. The abutments are so mounted that proper adjustments are insured for satisfactory sewing operations on different thicknesses of materials, the needle and awl receiving slots being always centered in alignment with the needle and awl paths.

Referring to the drawings, the abutments of the work support are indicated at 10 and 12, and the abutment 10 is located for movement on the abutment 12 along the work supporting surface of the abutment 12 to enable the work engaging surface of the abutment 10 to be moved toward and from the slot 8 in the abutment 12.

It is apparent that for the thickness of material, indicated in Fig. 1, the position of a bag corner as presented to the needle and awl while the bag is being guided on the work support will produce a satisfactory seam, the stitches of which will be suitably embedded in the material of the parts operated upon to form a secure connection. If, however, the thickness of the side surface abutting part, indicated at 14, is substantially increased to that illustrated by the dot-dash line of Fig. 1, then the end abutting part 16 will be held out of the needle path or will be presented to the machine in such a way that an insecure seam will be formed. In order to avoid this difficulty, the abutment 10 is moved upwardly along the work engaging surface of the abutment 12 away from the needle slot 8 to provide a greater distance between the abutment 10 and the slot 8 in the abutment 12, as illustrated in Fig. 2. Thus, the bag corner will be presented to the needle and awl at a position where the stitches will be inserted more deeply in the material at the end-surface of the end abutting part 16 and at the same time be located at least as deeply within the substance of the side abutting part 14. Where a substantial increase in thickness occurs, however, while the position of the abutment 10 is being changed, the needle slot 6 may be carried away from the path of the needle so that a further change may be required in the position of the abutment 10 before the needle and awl may operate properly.

To enable a further change to be made in the position of the needle slot 6 of the abutment 10 to center the slot 6 with respect to the needle path without changing the position of the slot 8 relatively to the needle path, the entire work support is guided for arcuate movement about the slot 8 as a center, thus causing the slot 6, when abutment 10 is moved, to swing until it coincides with the needle path without moving the slot 8 out of the needle path. With these two simple adjustments, changes in materials operated upon may be accommodated for a wide variation of thicknesses without interfering with

the operation of the machine or requiring careful or skillful manipulations to be made during adjustments.

To support and guide the abutment 10 along the work engaging surface of the abutment 12 toward and from the needle receiving slot 8 in the abutment 12, the abutment 12 is transversely slotted and provided with rectilinear side guideway surfaces 18. Projecting beneath the lower surface of the abutment 12 and engaging opposite rectilinear surfaces 18 thereof are two sides of a hollow rectangular slide 20 from which the abutment 10 projects upwardly at right angles, the central section of the slide being cut out to receive a downwardly extending portion on the abutment 12 for purposes to be described hereinafter. The guideway surfaces 18 insure a rectilinear movement of the abutment 10 along the work supporting surface of the abutment 12 so as to provide greater space between the abutment 10 and the needle receiving slot 8, for thicker work, and to enable the abutment to be moved closer to the needle receiving slot 8, with thinner work. Thus, it is possible to insert stitches in the part 16 of a bag with threads exposed at a uniform distance from the abutting end of the part 16, regardless of the relative thickness of the side abutting bag part 14.

To prevent distortion of the bag part and to provide support for the edge of the bag part 14 along the apex formed by the work engaging surfaces of the abutments, the abutment 12 has an integral tongue 22 sliding within side grooves 24 in a cut-away portion of the abutment 10. The tongue 22 is made with sufficient length to project rearwardly behind the work engaging surface of the abutment 10 with any adjustment of the relative positions of the abutments.

The abutments 10 and 12 of the work support are mounted upon and are adjustably clamped in fixed relation to a U-shaped bracket 26 formed with arcuate arms carried by the frame of the sewing machine indicated at 28. To clamp the abutments in fixed position on the bracket 26, a machine screw 30 passes through the slot 29 in the abutment 12 and is received within a threaded opening in the bracket 26. As a further means for preventing displacement of the abutment 10, the sides of the slide 20 are provided with flanges 31 underlying the abutment 12 so that, when the screw 30 is tightened, both abutments will be clamped to the bracket 26.

The arcuate arms on the bracket 26 form slides moving within correspondingly shaped grooves or guideways 32 in the frame 28, the center of curvature of the slides being located in the needle receiving slot 8 of the abutment 12. To secure the bracket in adjusted position on the machine frame 28, the machine frame has arcuate slots, one of which is indicated at 34 to receive pairs of spaced bolts 36. When the bolts are loosened and the arcuate slides moved in their guideways, the needle receiving slot 6 may be moved into alignment with the path of the needle and awl without changing the position of the slot 8.

In certain types of work, curved contours may be encountered, as illustrated in Fig. 9, requiring a convex surface on one of the abutments to fit within a concavity of one face of the bag. To render the machine readily adaptable for sewing different contours and curvatures of bag faces, the abutment 10 has a convex work engaging plate 38 screwed to its front face and the abutment is cut away behind the plate with an open-

ing sufficiently large to clear the stitch forming devices during sewing operations. With an end abutting bag part 16 of greater thickness than that illustrated in Fig. 1 of the drawings, it is preferable to employ a plate 38 on the abutment 10 with a needle receiving slot 6 located further away from the abutment 12 than is illustrated, to enable the stitches to be inserted at sufficient depth in the material. By utilizing a removable plate in which the slot 6 is formed, different plates having needle slots at varying locations may be made and substituted conveniently when thicker or thinner bag parts are being sewed so that distortion of the bag parts as a result of insufficient support about the sewing point may be avoided for any type of material. Also, adjustments may be made in the depth or location of stitches under all conditions with the assurance that the seam will be inserted correctly so long as the needle and awl slots are in line with the needle and awl paths.

The needle receiving slots 6 and 8 in the work support abutments 10 and 12 are made with sufficient length and are located to insure that the feeding movement of the awl will readily be accommodated without employing slots of excessive length. In the illustrated machine, the slots 6 and 8 are so arranged that, during the penetrating stroke of the awl, the awl will pass close to the right ends of the slots and, during feed, the awl will move into line with the needle, bringing the awl close to the left ends of the slots. Thus, the slots will be located centrally of the work feeding movement of the awl in order to provide a maximum possible support for the parts of the bag surrounding the sewing point.

To facilitate locating the slots centrally of the feeding movement of the awl, the abutment 12 has a slide portion 40 (see Fig. 7) along its lower surface passing through the cut-out section of the abutment 10 and engaging a groove 42 in the bracket 26. The slide portion 40 and the guideway formed by the groove 42 are so arranged as to extend in a direction parallel to the feeding movement of the work and to the lengthwise dimension of the needle and awl receiving slots in the abutments. When the clamping screw 30 is loosened, the abutments may be moved as a unit to locate the needle and awl receiving slots 6 and 8 in the desired position along the line of the seam, the slot through which the screw 30 passes being of sufficient length to accommodate this adjusting movement. Thus, the work support abutments 10 and 12 are secured on the brackets and in fixed position relatively to each other against movement in two directions by the single clamping screw 30.

The nature and scope of the invention having been indicated and an embodiment of the several features in their preferred form having been specifically described, what is claimed is:

1. In a machine for sewing the corners of a bag or similar article having an end surface of one part abutting the side marginal surface of another part with stitches disposed at an angle to the abutting surfaces, the combination with stitch forming devices including a needle, of means for externally supporting the work parts operated upon with both faces adjacent a corner at an inclination to and intersected by the needle path, comprising abutments having angularly disposed work engaging surfaces formed with close fitting needle receiving openings to prevent distortion of the work parts while inserting stitches, and adjustable means for securing one of the abut-

ments in fixed position relatively to the other during sewing operations, the abutments being constructed and guided to cause the exposed threads of each seam to be located at a predetermined distance from the end of the end abutting part when different thicknesses of the side abutting part require change in the positions of the abutments.

2. In a machine for sewing the corners of a bag or similar article having an end surface of one part abutting the side marginal surface of another part with stitches disposed at an angle to the abutting surfaces, the combination with stitch forming devices including a needle, of means for externally supporting the work parts operated upon with both faces adjacent a corner at an inclination to and intersected by the needle path, comprising abutments having angularly disposed work engaging surfaces formed with close fitting needle receiving openings to prevent distortion of the work parts while inserting stitches, means for adjustably securing one of the abutments relatively to the other to enable the exposed threads of each seam to be located at a predetermined distance from the end of the end abutting part when the thickness of the side abutting part is changed, and a swinging mounting for the work supporting means for securing the supporting means in any of a number of angular positions centered about the needle opening in one of said abutments, to enable insertion of stitches with exposed threads located at a predetermined distance from the end of the side abutting part when the thickness of the side abutting part is changed.

3. In a machine for sewing the corners of a bag or similar article having an end surface of one part abutting the side marginal surface of another part with stitches disposed at an angle to the abutting surfaces, the combination with stitch forming devices including a needle, of means for externally supporting the work parts operated upon with both faces adjacent a corner at an inclination to and intersected by the needle path, comprising relatively fixed abutments having angularly disposed work engaging surfaces formed with needle receiving openings fitting closely with the size of the needle to prevent distortion of the work parts while inserting stitches, rectilinear guiding means for the first abutment disposed to direct movement of the first abutment toward or away from the needle receiving opening in the second and along the work supporting surface of the second, and means for clamping the first abutment in adjusted position relatively to the second abutment.

4. In a machine for sewing the corners of a bag or similar article having an end surface of one part abutting the side marginal surface of another part with stitches disposed at an angle to the abutting surfaces, the combination with stitch forming devices including a needle, of means for externally supporting the work parts operated upon with both faces adjacent a corner at an inclination to and intersected by the needle path, comprising relatively fixed abutments having angularly disposed work engaging surfaces formed with needle receiving openings fitting closely with the size of the needle to prevent distortion of the work parts while inserting stitches, rectilinear guiding means for the first abutment disposed to direct movement of the first abutment toward or away from the needle receiving opening in the second and along the work supporting surface of the second, and

a curved guideway for the work supporting means centered about the needle receiving opening in the second abutment, to enable the needle receiving opening in the first abutment after movement to be brought into line with the needle path.

5. In a machine for sewing the corners of a bag or similar article having an end surface of one part abutting the side marginal surface of another part with stitches disposed at an angle to the abutting surfaces, the combination with stitch forming devices including a needle, of means for externally supporting the work parts operated upon with both faces adjacent a corner at an inclination to and intersected by the needle path, comprising relatively fixed abutments having angularly disposed work engaging surfaces formed with needle receiving openings fitting closely with the size of the needle to prevent distortion of the work parts while inserting stitches, rectilinear guiding means for the first abutment disposed to direct movement of the first abutment toward or away from the needle receiving opening in the second and along the work supporting surface of the second, and a work supporting projection on the second abutment extending rearwardly behind the work engaging surface of the first abutment opposite the point of needle operation to prevent distortion of the work parts at the apex formed by the abutments in any adjusted position of the first abutment.

6. In a machine for sewing the corners of a bag or similar article having an end surface of one part abutting the side marginal surface of another part with stitches disposed at an angle to the abutting surfaces, the combination with stitch forming devices including a needle, of means for externally supporting the work parts operated upon with both faces adjacent a corner at an inclination to and intersected by the needle path, comprising relatively fixed abutments having angularly disposed work engaging surfaces formed with needle receiving openings fitting closely with the size of the needle to prevent distortion of the work parts while inserting stitches, rectilinear guiding means for the first abutment disposed to direct movement of the first abutment toward or away from the needle receiving opening in the second and along the work supporting surface of the second, and a convex plate secured to the first abutment, to enable sewing curved concave corners in the work.

7. In a machine for sewing the corners of a bag or similar article having an end surface of one part abutting the side marginal surface of another part with stitches disposed at an angle to the abutting surfaces, the combination with stitch forming devices including a needle, of means for externally supporting the work parts operated upon with both faces adjacent a corner at an inclination to and intersected by the needle path, comprising relatively fixed abutments having angularly disposed work engaging surfaces formed with needle receiving openings fitting closely with the size of the needle to prevent distortion of the work parts while inserting stitches, rectilinear guiding means on the second abutment for the first abutment substantially parallel to the surface of the second abutment and arranged to direct movement of the first abutment toward and from the needle receiving opening in the second abutment, and a curved guideway for the second abutment centered about the needle opening in said second abutment.

8. In a machine for sewing the corners of a bag or similar article having an end surface of one part abutting the side marginal surface of another part with stitches disposed at an angle to the abutting surfaces, the combination with stitch forming devices including a needle, of means for externally supporting the work parts operated upon with both faces adjacent a corner at an inclination to and intersected by the needle path, comprising abutments having angularly disposed work engaging surfaces, a bracket for supporting the abutments, and a single clamping means for securing the abutments in fixed positions relatively to each other and to the supporting bracket.

9. In a machine for sewing the corner of a bag or similar article having an end surface of one part abutting the side marginal surface of another part with stitches disposed at an angle to the abutting surfaces, the combination with a main frame and stitch forming devices in the frame including a needle, of means for externally supporting the work parts operated upon with both faces adjacent a corner at an inclination to and intersected by the needle path, comprising abutments having angularly disposed work engaging surfaces formed with needle receiving openings fitting closely with the size of the needle to prevent distortion of the work parts while inserting stitches, rectilinear guiding means on the second abutment for the first abutment for directing movement of the first abutment along the surface of the second abutment toward and from the needle receiving opening in the second abutment, a bracket to which the second abutment is clamped, and a curved guideway in the frame for supporting the bracket for movement transversely of the seam line about an arc cen-

tered in the needle opening of said second abutment.

10. In a machine for sewing the corner of a bag or similar article having an end surface of one part abutting the side marginal surface of another part with stitches disposed at an angle to the abutting surfaces, the combination with a main frame and stitch forming devices including a work feeding and penetrating instrument, of means for externally supporting the work parts operated upon with both faces adjacent the corner at an inclination to and intersected by the needle path, comprising abutments having angularly disposed work engaging surfaces formed with work penetrating instrument receiving slots fitting closely with the size of the work penetrating instrument to enable feeding movement of the said instrument while preventing distortion of the work parts during insertion of stitches, guiding means on the second abutment for the first abutment arranged to direct movement of the first abutment substantially parallel to the surface of the second abutment toward and from the slot in the second abutment, a bracket having a guideway for the second abutment extending parallel to the slot in the second abutment to enable the position of the slot to be located centrally of the work feeding movement of the penetrating instrument, means for clamping the second abutment to the guideway, and a curved guideway in the frame for supporting the bracket for movement about an arc centered in the slot of the second abutment to enable the slot in the first abutment to be brought into line with the path of the work penetrating instrument transversely of the seam line.

OTTO R. HAAS.
